VACUUM CLEANER DUST BAG

William V. Orr, Cleveland, Ohio; The Cleveland Trust Company and Adele Mary Orr, executors of said William V. Orr, deceased

Application January 29, 1930, Serial No. 424,318

4 Claims. (Cl. 150—3)

This invention relates to vacuum cleaners and particularly the dust bag used in connection with and forming a part of the cleaner.

Ordinarily the conventional vacuum cleaner 5 dust bag is formed from a porous material such as cloth or paper, having openings at each end, one of which is attached to the fan outlet of the cleaner mechanism and the other or discharge end of which is provided with a detachable closure member adapted to be supported on the handle of the cleaner. Such closure members are usually formed from a metal stamping in the shape of an open channel member which is adapted to receive the lips of the discharge end of the 10 bag in the channel of said member and to maintain them in closed relation. The ends of the channel member are more or less sharp and rough and are apt to scratch and mar furniture and wood work with which they come in contact in 15 the operation of the cleaner.

It is the object of this invention to provide a bag closure in which the closure member and bag is so formed and arranged that it is impossible to mar or scratch furniture, or other articles 25 which the bag closure may accidentally come in contact with.

In general my invention consists in the provision of an ordinary closure member which is adapted to lie in a pocket or to be covered and 30 concealed by a flap formed from the same material as the dust bag, and in this manner provide a guard and concealment for the closure member.

With these and other objects in view, the invention consists in the novel construction arrangement and combination of parts hereinafter described and illustrated in some of its embodiments in the accompanying drawing and particularly pointed out in the appended claims.

In the drawing, Fig. 1 is a perspective view of a 40 vacuum cleaner having a dust bag embodying my improved bag closure; Fig. 2 is a side elevational view of the discharge end of the bag in closed position; Fig. 3 is a perspective view of the discharge end of the bag showing the closure member uncovered and partly removed; Fig. 4 is a section view taken on line 4—4 Fig. 2.

My improved bag closure is shown in connection with a conventional portable vacuum cleaner having a casing 1 supported on casters 2 for 50 the purpose of easily moving the cleaner over the surface to be cleaned.

The casing 1 houses a suitable suction fan and motor which provide sufficient suction at the nozzle of the cleaner to effect the cleaning operation. The outlet 3 from the cleaner fan chamber

is connected to the dust bag 4 which is secured at its upper discharge end to the handle 5 to the cleaner by means of the detachable spring 11 carried in the tab 12 that is sewed to the bag.

The upper or discharge end of the cleaner bag 60 is provided with a flap 6 that is sewed to the bag along one side as at 14 and at the opposite edges 8, forming a reversible pocket or flap which may be turned inside out to expose the bag opening, and which normally assumes the position wherein the 65 bag opening is at the bottom of the pocket so formed. The cooperating elements 9 and 10 carried on the bag and flap respectively provide a snap fastener for the latter. The lips of the bag are provided with a considerable thickness of material at their end portions for reception in the channel of the clamp 7. This portion of the bag is formed by stitching the bag end over the flexible cords 13.

With the flap or pocket 6 in the open position 75 as shown in Fig. 3 closure of the bag is effected by folding the bag with two sides lying parallel with each other as illustrated and by then slipping the channel member 13 over these ends. When the bag is thus closed the pocket or flap 80 is reversed, its fastener secured and the channel member is then completely concealed and covered.

In this manner a simple, inexpensive bag closure is provided in which the channel closure 85 member is completely concealed, covered and guarded, so that its edges cannot come in contact with and scratch furniture and other articles, and at the same time the appearance of the machine generally and the bag particularly is greatly 90 enhanced by reason of this construction.

Furthermore, it is to be understood that this particular form of apparatus shown and described, and the particular procedure set forth are presented for purposes of explanation and 95 that various modifications of said apparatus and procedure can be made without departing from my invention as described in the appended claims.

Having thus described my invention, what I claim is:

1. A vacuum cleaner dust bag having lips at one end defining a dust and litter discharge opening, and a removable clamp or closure member operatively engaging the lips of said bag for holding them in closed position, said bag having a 105 pocket closed on three of its edges and formed about the discharge opening of the bag for receiving said clamp within its confines and guarding the ends thereof from coming in contact with furniture and other articles during the operation 110

of the cleaner, the pocket of said bag being reversible for exposing said clamp as a step prior to its removal.

2. A vacuum cleaner dust bag having a substantially rectangular pocket formed in one end thereof and closed along three of its edges with the opening of the pocket located on one side of the bag at a point adjacent to the end thereof, said bag having lips located in the bottom of the pocket defining a dust and litter discharge opening normally facing the bottom of the pocket, detachable fastening means for securing the free marginal portion of the pocket to said bag, and a removable clamp or closure member operatively engaging the lips of the bag for holding them in closed position, the pocket of said bag being reversible for exposing said clamp as a step prior to its removal and the closed sides of said pocket being effective to guard the ends of said clamp and prevent its removal when said bag is in its operative position.

3. A filter for a suction cleaner comprising, an air pervious dust bag having an inlet opening at one end and a pair of lips at its other end defining a dust and litter discharge opening, a removable slidably fitted clamp or closure member normally engaging the lips of said bag for holding them in closed position, means comprising a part

fixedly and permanently attached to the material of said bag for supporting its discharge end, and means permanently attached to and forming a part of said bag for covering and concealing said clamp whereby the ends thereof are guarded against contacting and scratching articles of furniture and the like, said last named means being also effective for preventing the removal of said clamp when the bag is in its operative position.

4. A filter for a suction cleaner comprising, an air pervious dust bag having an inlet opening at one end and a pair of lips at its other end defining a dust and litter discharge opening, and closure means for said opening, said bag having a part fixed thereto adjacent to the discharge opening thereof and adapted for occupying two positions, one corresponding to the bag emptying position in which the aforesaid bag part is turned back so that the bag lips define a clear and unobstructed opening upon the removal of the bag closure means and the other position corresponding to the position occupied by the bag during the operation of the cleaner in which the stated bag part completely covers the stated bag closure means whereby such closure means is concealed and prevented from contacting and scratching articles of furniture and the like.
